ALFRED R. ULP, OF PASADENA, CALIFORNIA

SPRING BOOT

Application filed January 18, 1927. Serial No. 161,860.

My invention relates to boots for laminated vehicle springs, and a purpose of my invention is the provision of a spring boot which affords superior means in respect to existing boots for the protection, lubrication and permanent preservation of springs against deterioration by exposure to the elements.

I will describe only one form of spring boot embodying my invention, and will then point out the novel features thereof in claims.

In the drawings—

Figure 1 is a view showing in side elevation a portion of a vehicle spring having applied thereto one form of spring boot embodying my invention, and with portions of the latter in section;

Figure 2 is a view showing the spring boot in bottom plan and in applied position to a vehicle spring;

Figures 3 and 4 are sectional views taken on the lines 3—3 and 4—4 of Figure 1;

Figure 5 is an enlarged detail sectional view of a part of one of the clamping devices embodied in the boot shown in the preceding views;

Figure 6 is a vertical sectional view of the liner embodied in the spring boot and in applied position to a vehicle spring;

Figure 7 is a detail perspective view on a reduced scale showing the liner in unfolded position;

Figure 8 is an enlarged view showing in top plan the lubricant port of the boot and the control device therefor;

Figure 9 is a sectional view taken on the line 9—9 of Figure 8; and

Figure 10 is a sectional view taken on the line 10—10 of Figure 8.

Similar reference characters refer to similar parts in each of the several views.

Referring specifically to the drawings, my invention in its present embodiment comprises a liner designated generally at L and comprising a sheet 15 of suitable length and width constructed of any material, preferably one which is oil- and water-proof, and having secured to the inner side thereof a relatively narrow strip of absorbent material 16, and a relatively wide strip of similar

material 17. It will be noted that these two strips are secured at the opposite ends of the sheet so as to provide an intervening space which, in the applied position of the liner to a vehicle spring, provides a chamber in which grease or other lubricant is adapted to be stored. A pair of metallic straps 18 extend from one longitudinal edge of the liner, while loops 19 extend from the opposite edge, the latter cooperating with the straps in providing means by which the liner can be secured in wrapped position upon a spring. The portions of the longitudinal edges of the sheet 15 are recessed, as indicated at 20, with adjacent portions of the strip 17 likewise recessed. The purpose of these recessed portions is to provide an opening in the liner when the latter is in applied position upon a spring in order that lubricant can be injected through the liner to the spring and in a manner to saturate the strip 17 so that the latter will function as a reservoir for supplying oil to the outer ends of the leaves of the spring.

J designates generally a jacket adapted to be wrapped about the liner L and consisting of a sheet 21 of leather or some other suitable water- and oil-proof material. In its applied position to the spring the jacket is held in covering relation to the liner by a plurality of leather straps 22 extending from one longitudinal edge of the sheet 21 at regular spaced intervals and engaging correspondingly positioned buckles 23 projecting from the opposite longitudinal edge of the sheet. For clamping the extreme ends of both the liner and the jacket in such snug relation to the spring as to effectively seal the boot against the outward passage of any lubricant contained therein or the inward passage of water, air and dust, I provide a pair of clamping elements designated at E and E' respectively, and as the two are identical in construction a description of one will suffice for both. Each element comprises a frame 24 substantially U-shaped in form and constructed of metal. This frame is secured by means of a rivet 25 to the outer side of the jacket J, a rivet also being employed to secure one end of a metal strap 26 to the frame. This strap

60

95

100

is adapted to encircle the jacket with its opposite end extending into a slot 27 of a stub shaft 28, the latter being journaled in the parallel portions of the frame 24 and provided at one end with a screw head 29 and at the opposite end with a smaller head 30. The split portion 27 of the shaft 28 permits the shaft to be contracted sufficiently to allow the passage of the head 30 through the corresponding opening of the frame 24 so that when the head is in this applied position the tendency of the shaft to expand will lock the head against accidental removal from the frame so that the shaft as a unit is secured in journaled position within the frame. The head 29 carries a ratchet wheel 31 adapted to be engaged by a pawl 32 pivoted on the frame at the point indicated at 33 and provided with a protuberance 34 which is positioned to be engaged by the jacket J so as to utilize the expansive action of the jacket in maintaining the pawl in locking engagement with respect to the ratchet wheel so that rotation of the shaft 28 is permitted in one direction only, and in such direction as to allow winding of the strap 26 thereon to effect a shortening of the latter in constricting the ends of the jacket and liner. It will be understood that the rotation of the shaft 28 can be effected through the application of a screwdriver or some other suitable tool to the screw head 29.

For the purpose of permitting a lubricant to be injected into the boot from time to time in order to insure the proper lubrication of the leaves of the spring, the jacket at a point adjacent the outer end of the spring is provided with an opening 35 (Figure 9), while a metal plate 36 of substantially U shape and having a depressed marginal flange 37 is secured to the jacket by rivets 38 so that an opening 39 forming in the plate registers with the opening 35. The metal immediately surrounding the opening 39 is depressed to form a pocket in which is received the out-turned flange of an eyelet 40 so that the eyelet will be flush with the top surface of the plate 36, the eyelet being extended through the opening 35 and crimped as clearly shown in Figure 9. Upon the plate 36 is pivoted at the point indicated at 41 a control device or shutter in the form of a plate 42 provided with an opening 43 which in the open position of the plate as shown in Figure 8 is adapted to register with the eyelet 40 in order that the spout of an oil can may be inserted and lubricant supplied to the liner through the opening defined by the recessed portions 20. The plate 42 is movable from the open position shown in Figure 8 to a closed position in which its opening 43 is out of registration with the eyelet 40. The two positions of the plate 42 are defined by an inturned lip 44 formed on the free end of the plate and projecting into the open end of the plate 36

for engagement with either of its side walls 45. The plate 42 is urged to closed position by a spring 46 having its coiled portion 47 disposed beneath and at one end of the plate 36, and its free ends projecting into a pocket 48 formed in the plate. An upstruck loop 49 is formed in the pocket to receive one of the free ends of the spring while a downstruck loop 50 in the plate 42 receives the other end, so that the ends in normally tending to spread under the action of the coiled portion 47 urge the plate 42 to closed position. The loop 50 projects into a slot 51 in the pocket 48 for the purpose of minimizing the height of the plate 36. By this arrangement the spring functions to normally close the plate 42, but is yieldable to permit the plate to be pushed to open position by the spout of an oil can or other instrument. It will be understood that when the spout is removed the spring will function to automatically close the plate, thus insuring the closing of the eyelet 40 to exclude water and dirt from the interior of the boot.

In practice, the liner L is applied to approximately one-half of a leaf spring S as illustrated in Figure 1, the liner being wrapped about the spring so that its longitudinal edges are disposed at the upper side of the spring and in close proximity to each other to form a joint of minimum width. The liner can be secured in this position through the extension of the straps 18 through the loops 19 followed by the bending of the straps reversely upon themselves, as clearly illustrated in Figure 6. In this position of the liner the absorbent strip 16 is disposed adjacent the medial portion of the spring, while the wider strip 17 is disposed adjacent the outer end of the spring to perform the double function of sealing the outer end of the boot against the inward passage of water, dirt and the like thereinto and the reception of a portion of the oil introduced into the boot through the eyelet 40 so that it can function as a storage reservoir to maintain a supply of oil to the outer ends of the spring leaves. It is important to note that in the applied position of the liner the strips 16 and 17 function in connection with the sheet 15 to provide a chamber which extends completely around the spring and in which lubricant can be stored for the purpose of providing further means for lubricating the leaves of the spring.

Following the application of the liner L the jacket J can now be applied and in such manner that its longitudinal edges are disposed at the lower side of the spring as illustrated in Figures 2 and 3. In this manner the intermediate portion of the jacket spans the joint of the liner, thus sealing the intermediate portion of the liner against passage of lubricant outwardly over the boot or the passage of water inwardly of the boot. The

ends of the jacket as well as the ends of the liner are constricted by the application of the clamping elements E and E', the straps 26 through the manipulation of the shafts 28 being constricted to such a degree that they will function to clamp the boot ends in thorough engagement with the spring. In this manner the boot ends can be sealed against the passage of the lubricants outwardly of the boot ends and more important the passage of water or any other liquid inwardly of the boot ends. Thus the boot not only provides a lubricating means for the spring, but it permanently preserves the 15 spring against deterioration through exposure to the elements as long as the boot remains intact.

Although I have herein shown and described only one form of spring boot embodying my invention, it is to be understood that various changes may be made therein without departing from the spirit of the invention, and the spirit and scope of the claims.

25 I claim:

1. A spring boot comprising a sheet of flexible and liquid-proof material constituting a liner adapted to embrace a portion of a spring so that its longitudinal edges are in close proximity to each other at one side of the spring, a second sheet of flexible and liquid-proof material constituting a jacket and adapted in applied position to a spring to surround the liner in such manner that the longitudinal edges of the jacket are disposed in close proximity to each other and at a side of the spring opposite to the longitudinal edges of the liner, means for securing the liner in wrapped position on a spring, and means for securing the jacket in wrapped position on the liner in a manner to seal the ends of the liner and jacket about the spring.

2. A spring boot comprising a jacket, a liner within the jacket having lubricant absorbing strips on the inner surface thereof and at the opposite ends, operating to seal the ends of the liner when applied to a spring, and one of the strips being disposed adjacent 45 openings in the jacket and liner through which a lubricant can be supplied to a spring and to one of the strips so that the latter functions as a lubricant reservoir.

3. In a spring boot, flexible members adapted to house a portion of a spring, clamping elements embracing the members and comprising straps, each having one end secured to one of the members, and a device for coiling the opposite end to constrict the strap into clamping relation to the members, said device including a stub shaft to which the strap is secured, and pawl and ratchet means permitting one way strap winding rotation of the stub shaft.

65 4. In a spring boot, flexible members adapt-

ed to house a portion of a spring, clamping elements embracing the members and comprising straps, each having one end secured to one of the members, and a device for coiling the opposite end to constrict the strap into clamping relation to the members, said device including a stub shaft to which the strap is secured, and pawl and ratchet means permitting one way strap winding rotation of the stub shaft, and including a pawl having a protuberance which is engageable with the members to utilize the expansive action of the members in maintaining the pawl in one way locking position.

5. In a spring boot, flexible members adapted to house a portion of a spring, and clamping elements embracing the members and comprising straps each having one end secured to one of the members, and a device for coiling the opposite end to constrict the strap into clamping relation to the members, said device comprising a frame, a shaft journaled in the frame and having heads on its ends, a portion of the shaft being split to receive the strap ends and to permit a reduction in the diameter of one of the heads to allow it to be passed through and locked in a portion of the frame, a ratchet wheel fixed on the shaft and a pawl pivoted on the frame, and normally engaging the wheel to lock the latter and consequently the shaft against rotation in one direction.

6. In a spring boot, flexible members adapted to house a portion of a spring, and clamping elements embracing the members and comprising straps each having one end secured to one of the members, and a device for coiling the opposite end to constrict the strap into clamping relation to the members, said device comprising a frame, a shaft journaled in the frame and having heads on its ends, a portion of the shaft being split to receive the strap ends and to permit a reduction in the diameter of one of the heads to allow it to be passed through and locked in a portion of the frame, a ratchet wheel fixed on the shaft and a pawl pivoted on the frame having a protuberance engaging the members in a manner to utilize the expansive action of the members in maintaining the pawls in a position to lock the wheel against rotation in one direction.

7. A spring boot comprising a sheet of flexible and liquid-proof material constituting a liner adapted to embrace a portion of a spring so that its longitudinal edges are in close proximity to each other at one side of the spring, a second sheet of flexible and liquid-proof material constituting a jacket and adapted in applied position to a spring to surround the liner in such manner that the longitudinal edges of the jacket are disposed in close proximity to each other and at a side of the spring opposite to the longitudinal edges of the liner, means for securing the liner in wrapped position on the spring,

means for securing the jacket in wrapped position on the liner, and clamping elements embracing the ends of the jacket for securing the ends of both the jacket and the liner in sealing position with respect to the spring.

- 5 8. In a spring boot, a spring embracing member, a second member embracing the first member, registering openings in the members through which a lubricant can be supplied interiorly of the first member, a plate secured to the second member and having an opening registering with the opening of the said member, a second plate pivoted on the first plate to occupy either of two extreme 10 positions, the second plate being provided with an opening adapted to register with the opening of the first plate when in one extreme position, and means for yieldably urging the second plate to a position in which its opening is out of registration with the opening of the first plate.
- 15 9. In a spring boot, a flexible member adapted to house a portion of a spring, a clamping element embracing the member and comprising a strap, and a device with which one end of the strap is fixedly associated, having means for coiling the opposite end of the strap to constrict the latter in clamping relation to the member, said device including a 20 stub shaft upon which said opposite end of the strap is adapted to be wound, and pawl and ratchet means for allowing one way strap winding rotation of the stub shaft.
